UNITED STATES PATENT OFFICE

2,514,466

FREIGHT LOAD BRACE

Robert J. Bildhauer, Pittsburgh, Pa.

Application April 25, 1947, Serial No. 743,952

1 Claim. (Cl. 105—369)

1. A freight load brace.

This invention relates generally to portable bulkheads and more particularly to freight load braces for use in railway freight cars to prevent the displacement or shifting of the merchandise in transit.

The principal object of this invention is the provision of a railway freight load brace that is laterally adjustable so as to be adaptable for use in freight cars of varying width.

Another object is the provision of a railway car freight load brace adapted for adjustment to extend from one side wall of the car to the other to enable it to be readily secured to the car to prevent the shifting of merchandise in transit and to be easily removed at the end of the trip.

A further object is the provision of a portable bulkhead that may be used repeatedly and which will withstand abuse in service.

Another object is the provision of a portable bulkhead which is simple in construction, economical to manufacture, and is readily applied and removed from service.

Other objects and advantages appear hereinafter in the following description and claim.

A practical embodiment illustrating the principles of this invention is shown in the accompanying drawing wherein:

Fig. 1 is a view in front elevation illustrating the structure of the bulkhead comprising this invention.

Fig. 2 is a view in side elevation of the structure shown in Fig. 1.

Fig. 3 is a plan view of the structure shown in Fig. 1.

Fig. 4 is an enlarged detailed view showing the angularly disposed brace pivotally secured to the center of the bulkhead.

Referring to the drawings the bulkhead comprising this invention is made up of a plurality of angle irons or posts 1, 2, and 3. In practice these angle irons are preferably made from three-quarter inch steel with two inch flanges. A series of tubes 4, 5, 6, 7, and 8 have their ends welded to the angle iron 1 in uniform spaced relation as illustrated in Fig. 1 to form a series of rails. These tubes or rails are preferably made from standard pipe an inch and a quarter inside diameter and their left ends are welded to the inner faces of the flanges 10 and 11 of the angle iron 1.

Each of these tubes or rails is also welded to the outer face of the flange 13 of the angle iron 2 in uniform spaced relation as illustrated in Fig. 1 for the purpose of providing a bulkhead structure having vertical angle iron posts 1 and 2 and a series of horizontal tubular rails, tubular rails

4 to 8 being welded to the vertical angle iron post 2 to position the latter a little greater than one-half the distance of the length of these rails from the vertical post 1.

5 A vertical angle iron end post 3 has also welded to its inner flange faces a series of horizontal rails 14, 15, 16, 17, and 18. These rails are uniformly spaced along the length of the post 3 so that they may be concentrically aligned with their respective corresponding rails 4 to 8. The rails 14 to 18 are welded to the inner faces of the flanges 19 and 20 of the post 3 and are preferably constructed of standard pipe approximately one inch inside diameter so that they may telescope within the ends of the rails 4 to 8 as shown in Figs. 1 and 3, thus providing a section on the end of the bulkhead which is movable longitudinally of the rails for the purpose of being expanded or contracted to engage the side walls of a freight car.

10 20 The rails 14 to 18 are preferably telescoped so that their free ends extend within their corresponding rails 4 to 8, to the position indicated at 21 in Fig. 3. When the bulkhead is expanded to its greatest dimension in order to prevent the movable bulkhead section from becoming disengaged from the other portion of the bulkhead a pair of chains 22 and 23 are welded at one end to the vertical angle iron post 3 and their other ends to adjacent the ends of the rails 4 and 8 respectively.

25 The bottom of the centrally disposed post 2 has its flange 13 turned upwardly and inwardly as shown at 24 to form a foot which is provided with a hole 25 for receiving a nail or spike to permit the foot to be nailed to the floor of a freight car. The side of a foot 24 may be welded to the flange 12 as indicated at 26 for the purpose of strengthening the foot of this post.

30 35 The flanges 10 and 20 of the vertical angle iron end post 1 and 3 respectively are provided with a series of holes shown at 27 in Figs. 1 and 2 some of which are placed closely adjacent the horizontal rails indicated by dotted lines. The holes 27 should not be placed too close to the horizontal rails as they would tend to make it difficult to insert and withdraw nails through these holes in the posts from the sides of the freight car.

35 40 At approximately three fourths of the distance up the center angle iron post 2 a ring or bail 28 is welded to the flange 12 as illustrated in Fig. 4. Prior to welding the ring 28 in place, it is inserted through the hole 29 of the projecting portion of the vertical flange 30 of the angle brace 31 which 45 is made up of a material similar to that of the

post 1 and is provided with the flanges 30 and 32. The lower end of the flange 32 is provided with an extension or foot 33 disposed at an angle to the flange 32 and provided with a hole 34 for receiving a spike to permit the foot of the brace member 31 to be nailed to the floor of a freight car.

It is preferable to employ double-headed nails wherein two heads are formed in tandem on the nail or spike which permits the latter to be driven through the holes provided in the angle iron members of this bulkhead but limits the extent to which these nails may be driven and still provides a head readily adaptable to be used for removing the nails by means of a claw hammer.

When the merchandise is being placed in a freight car it is ordinarily stored against the end of the car and is maintained substantially uniform across the car. When the whole of the shipment of merchandise has been placed in the car the bulkhead comprising this invention is collapsed and set into the car against the merchandise. The vertical post 1 is first nailed to the left side of the car. The bulkhead is then expanded to permit the vertical post 3 to engage the right side of the car and it is then nailed in place. The foot 24 of the center post 2 is then nailed to the floor and the lower end of the brace 31 is forced towards the merchandise to take up any tendency for the bulkhead to bulge in the center and its foot 33 is then nailed to the floor. Thus, by nailing 4 members directly to the floor and side walls of the freight car a very strong and relatively light bulkhead is provided to properly brace the merchandise within the car and all that is necessary to remove the bulkhead is the use of a claw hammer to remove the double-headed nails.

The multiple nailing of the vertical end post together with the angular brace provides a very strong structure for shoring the merchandise. It has been found in practice that this bulkhead does not lend itself to any other use as does the ordinary bulkhead made of lumber which frequently finds its way to a fire for warming workers during cold weather or for other uses which cause them to be improperly removed from their intended use. It has also been found that the tubular rail structure in combination with the angular vertical post structure provides a very rigid shoring device that will withstand material impact without destruction. Blocks have been employed to hold the posts in position but

it has been found to be far better to nail the angle members directly to the walls and floor.

I claim:

A brace for retaining freight articles in one end of a vehicle having floor, side and end walls consisting of two telescoping units, one unit composed of a vertical angle end post, a series of spaced horizontal tubular rails with their ends set against one flange and engaging the other flange of the angle end post and permanently secured thereto, an intermediate post permanently secured to each of said tubular rails intermediate of their ends, the other unit composed of a second vertical angle end post and a second series of spaced horizontal rails axially aligned with the tubular rails of the first unit and having their ends set against one flange and engaging the other flange of the angle of said second end post and permanently secured thereto, the size of the rails of the second series being selected to telescope within the tubular rails of the first series to complete the brace and adjustably position the end posts against the side walls of the vehicle, means defining a series of openings in one flange of each end post to receive fastening means to temporarily secure the end posts to the side walls for substantially the full length of said posts, and a support member extending rearwardly of and pivotally connected to the intermediate post and extending to the floor, and foot flanges on the bottom of said intermediate post and the bottom of said rearwardly extending support member to receive securing means for fastening the foot flanges to the floor of the vehicle.

ROBERT J. BILDHAUER.
